UNITED STATES PATENT OFFICE.

JEAN F. WEBB, JR., OF NEW YORK, N. Y., ASSIGNOR TO THE INTERNATIONAL SIGNAL COMPANY, INCORPORATED, (FORMERLY ELECTRIC SIGNAGRAPH & SEMAPHORE CO., INCORPORATED,) OF NEW YORK, N. Y.

TRAIN CONTROLLING AND STOPPING SYSTEM.

1,125,418.

Specification of Letters Patent.

Patented Jan. 19, 1915.

Application filed January 18, 1912. Serial No. 671,859.

To all whom it may concern:

Be it known that I, JEAN F. WEBB, Jr., residing at New York, in the county of New York and State of New York, have invented 5 certain new and useful Improvements in Train Controlling and Stopping Systems, of which the following is a specification.

Generally the invention includes a train carried apparatus in which is an air valve 10 that communicates with the train pipe of the air brake system and is normally held in its closed position by suitable devices that coöperate with the valve stem, the holding devices being releasable by a plunger that 15 engages a fixed track stop or tripping ramp along the right of way. The train carried mechanism also includes an automatic resetting device which, when operated by a controlled track fixture, resets the holding 20 devices, thereby closing the air valve and preventing its further action. In practice, the controlled track fixture is set a predetermined distance from the tripping ramp to reset the air valve and its holding device 25 almost instantly after the tripping ramp has been engaged by the plunger to release the holding devices. In this manner, the application of the brakes, unless the controlled track fixture be in its "danger" position, 30 does not take place. If the controlled track fixture be in its "danger" position, the resetting devices do not come into action and after the fixed ramp is passed by the releasing plunger the air valve will remain open, 35 and permit the application of the brakes.

The invention also includes a manually operative device that coöperates with the resetting mechanism of the train carried fixture whereby the engineer may reset the 40 same from the cab, subject, however, to the action of a speed controlled lock that prevents the operation of the manual resetting device when the speed of the train is above a predetermined minimum.

The invention furthermore provides a system and apparatus embodying those novel details of construction, combination and arrangement of parts, all of which will be first fully described and then be specifically 50 pointed out in the appended claims, reference being had to the accompanying drawings, in which:

Figure 1. is a view showing the invention in elevation, looking forward to-

ward the pilot of the locomotive. Fig. 2, is 55 a side elevation of one set of track mechanism. Fig. 3, is a horizontal section on the line 3—3 of Fig. 4. Figs. 4, 5, and 6, are vertical cross sections on the lines 4—4, 5—5 and 6—6 respectively of Fig. 3, looking in 60 the direction of the arrow A. Fig. 7, is a cross section on the line 7—7 on Fig. 6. Fig. 8, is a cross section on the line 8—8 on Fig. 6. Fig. 9, is a detail section on the line 9—9 of Fig. 1. Fig. 10, is a cross section on the 65 line 10—10 of Fig. 9. Fig. 11, is a side elevation largely diagrammatic, illustrating the speed controlled latch for the engineer's releasing rod, the direction of movement of the train being indicated by the arrow B. 70 Fig. 12, is a detail view taken on the line 12—12 of Fig. 11.

In the drawings like numerals and letters of reference indicate like parts in all of the figures.

The mechanism in general includes a train carried apparatus, a controlled track fixture for resetting purposes, and a fixed tripping ramp adjacent to the track for tripping the air valve releasing plunger to release the 80 holding device and permit the air valve to open and thereby operate the brakes.

The train fixture embodies a mechanism inclosed in a suitable housing 1, that is secured by suitable bolts 2 beneath the buffer beam 3, adjacent to the pilot 4 of the engine. Mounted within the forward projection of the housing 1 is the oscillatable sleeve carrying shaft 6 that forms a part of the resetting mechanism. The construction of the 90 shaft and its mounting is substantially the same as that disclosed in and forming the subject-matter of my copending application filed on the eighteenth day of January, 1912, Serial No. 671860, and in the present application I make no claim *per se*, to such shaft construction, as the same *per se*, constitutes no part of the present invention.

The shaft is mounted to oscillate in plug bearings 7 at each end of the housing extension 5, and between which bearings the shaft 6 carries two sleeves 8, each of which has a plunger or head 9 at the end adjacent to the respective bearings 7. Each head 9 has a peripheral quarter circle groove 10 to receive the casing stop pin 11 which limits the turning motion of the sleeve to approximately 90°. Each sleeve 8 is also provided

with a longitudinal slot 12 terminating, adjacent to the head 9, in a circumferential quarter-turn groove 13, in which the shaft pin 14 rides. The torsion spring 15 encircles the sleeves 8 and has its ends respectively fitted into the recesses 16 of the respective heads 9. Pins 17 prevent the bearings 7 from turning. The resetting shoe 18 is fitted onto the outer end of the shaft 6, while a radial finger cam 19 is secured on the other end of the shaft 6, the finger-cam 19 and shoe 18 holding the bearings 7 in place in the housing part 5.

Mounted within the housing is an air-operated valve device which comprises a valve casing 20 that is bolted at 21 to the housing and has a boss 22 which is provided with a chamber 23 into which the connection 24 from the train pipe of the air brake system (not shown) leads. The chamber 23 has a valve seat 25 at its mouth, and the chamber is normally closed by the valve 26, whose stem 27 projects through the adjusting plug 28 to the outside of the casing 20. The casing 20 has a discharge chamber 29 that delivers into the exhaust pipe 30.

Mounted in the housing 1 is a main shaft 31 which supports the valve holding cam 32. The cam 32 is keyed to the shaft 31 to turn with it. The cam 32 has a downward projection to be engaged by the mechanical trip bar or plunger, hereinafter described. The shaft 31 also carries a locking cam 33 that has a latch recess 34 to receive the spring latch bar 35. The latch device includes a casing 36 into a chamber 37 of which, the latch bar 35 projects. The latch bar 35 has a shoulder or disk portion 38 within the chamber, against which the spring 39 presses. The spring 39 also engages a washer 40 that is held in the casing 36, which in turn is secured at 41 to the main housing 1.

42 is the resetting lever that is keyed to the shaft 31 and cooperates with the resetting cam 19 to restore the parts to their normal position.

The housing 1 has inner bearing lugs 43 between which, on trunnions 44, the plunger 45 carrying casting 45 is secured. The casting 45 comprises a main body having an offset bracket-like upper portion 46 whose upper end is bifurcated at 47 to permit operation of the holding cam in the bifurcation. The main body portion 45 is bored longitudinally as at 48 and the lower end of the bore is restricted and squared in cross section as at 49. The valve releasing plunger 50, that cooperates with the valve holding cam 32, operates in the bore 48-49, and it has its lower portion 51 squared to work in the squared bore part 49, the upper end of which bore 48 is closed by a cap plate 52 that is removably held in place by screws 53 to retain the washers 54 between which the com-

pression spring 55, that holds the plunger 50 downwardly, works. The lower washer 54 abuts the upper end of the squared plug portion 51. The squared portion 51 of the plunger 50 only extends up to the washer 54 when the parts are in the normal position shown in Fig. 6, and from thereon up, the cross sectional configuration of the plunger 50, is circular.

It will be seen that the housing 1 has an abutment 60 which forms a stop to prevent movement of the casting 45, on its fulcrums 44, in one direction. In order to assist gravity in holding the casting 45 in its normal vertical position with its upper part 46 against the abutment 60, a spring 61 is attached at 62-63 to the housing 1 and casting 45 respectively.

In order that breaking of the plunger 50 may not render the mechanism inoperative as a train stop, the same is bored longitudinally at 56 to provide a duct, the lower end of which is closed, and the upper end of which is in communication with a pipe 57, that joins through any suitable flexible coupling 58, with the pipe 59 that is in communication with the train pipe of the air brake system at all times.

The pipes 24-59 may be connected through a joint 64 that is in turn connected with the train pipe (not shown). The bottom of the housing 1 is open at 65 to permit the casting 45 to swing from the full line position in Fig. 6 to that shown in dotted lines in the same figure, when the train is moving backward.

The arrows B in the drawings, indicate the normal direction of movement of the train, namely,—the forward movement.

The stationary track fixtures or ramps 66 are located at any desired place along the right of way, adjacent to the track 70. Adjacent ramps are usually spaced a predetermined distance apart. Each ramp 66 includes a base 67 that is secured at 68 to the ties 69 and on which base the ramp proper 66 is fastened.

The controlled track fixtures 71 may be of any approved type and operate in any desired manner so long as they include an arm 72 that normally projects into the path of the shoe 18, which arm is movable out of such path by suitable mechanical devices, under suitable control, when it is desired to stop the train. I prefer to employ such a mechanism as is shown in and forms the subject-matter of my application Serial No. 625,522, filed May 6, 1911.

Operation: In the drawings Figs. 4, 5 and 6, the full line designate the normal position of the parts, while parts are shown in their abnormal position by dotted lines. The direction of traffic is shown by the arrows B in these figures. When the train is running between ramps, the casting 45 that

carries the releasing plunger 51, hangs vertically; the contact shoe 18 is maintained in its vertical position by the balancing spring 15. When the train running in the direction of traffic reaches a tripping ramp 66, the enlarged portion 73 of the releasing plunger 51 engages the tripping ramp and rides up vertically over the same. The backward pressure on the plunger or the pressure acting against the line of travel, is taken up by the trunnions 44 and the thickened housing sides or abutment 60, together with the lugs 43 forming an extension thereof. As the plunger 51 rises, its top end engages the bottom projection of the valve closing and holding cam 32 and pushes it upwardly thereby releasing the valve stem 27 and the valve 26, whereupon the pressure of the air in the train line pipe 20 unseats the valve 26 which allows the air to escape through the outlet or exhaust pipe 30, thereby reducing the pressure in the train line pipe and sets the triple valves of the air brake system into action to stop the 25 train. If the contact arm 72 of the controlled track fixture is in the "stop" position, it will not engage the shoe 18 and the air continues to escape through the valve 26 until the train pipe pressure has been reduced to a predetermined point, whereupon the valve 26 will be reseated by the spring that surrounds its stem 27; the pressure cannot be again increased by the engineer until the train has been stopped and the contact 35 shoe 18 oscillated by hand to reset the valve closing cam to its normal position. If the contact arm 72 be in its "safe" position, it merely oscillates the contact shoe 18 backwardly, thereby causing the cam 19 to engage the resetting lever 42 and thus push it downwardly. This action on the lever 42 turns the shaft 31 to restore the holding cam 32 to its normal position and thereby brings it into its valve closing position, best 40 shown in full lines in Fig. 6. Owing to the proximity of the controlled track fixture to the tripping ramp the unseating of the valve 26 is followed so closely by the reseating thereof when the controlled track fixture is in its "safe" position, that not enough air escapes from the train line pipe 50 to cause an appreciable reduction of the air pressure in the train line pipe, and thus the triple valves of the air brake system are not brought into action to stop the train.

In order that the engineer may reset the mechanism after the air valve has been tripped and when the train is under control, I provide a resetting rod 74 that is adapted 60 to engage the projecting arm 75 of the locking cam 33. By pulling on the rod 74 the shaft 31 can be turned back to restore the parts to their set or normal position. In order that the rod 74 may not be pulled save 65 when the train is running below a prede-

termined speed, a latch device 76 is provided that engages a notch 77 in the rod 74 when the latch device 76 is held up by the governor 78. When the vehicle is running below a predetermined speed, the governor 78 will allow the latch 76 to drop out of the notch 77 and permit the rod 74 to be operated. The governor 78 may be driven in any suitable way from any moving part of the vehicle and a further description thereof is thought to be unnecessary. The rod 74 may be restored to its latched position when released by a spring 79.

When the engine is backing in a direction opposite to the direction of traffic, the releasing plunger 51 will, of course, engage the tripping ramps 66, but, owing to the fact that the casting 45 is fitted at its upper end on the trunnions 44, it is free to swing backwardly and the plunger 51 will not be raised vertically but will cause the casting 45 to swing to the dotted line position indicated in Fig. 6, thus carrying its parts forwardly and upwardly in a curve whose center is in the center of the trunnions 44; hence the top of the plunger 51 will not engage the lower projection of the holding cam 32 and the valve 26 will not be affected. After the ramp has been passed, gravity assisted by the spring will immediately restore the casting 45 and its carried parts to their normal positions.

From the foregoing, it will be observed that should the casting 45 and its carried parts become broken and thereby drop away from the housing, the flexible connection 58 will break, thus reducing the train pipe pressure to actuate the triple valves of the air brake system and set the brakes. Should the plunger 51 break off, the air from the duct 56 will escape and the same action on the air brake system above referred to will take place. Should the arm 72 of the controlled track stop become broken, the train as it passes the same will be stopped.

In this form of my invention, the contact shoe 18 oscillates in a vertical plane within the line of clearance of the buffer beam so that unintentional oscillation is practically eliminated. When the air valve is closed, or in its normal position, any oscillation of the shoe 18 has no effect whatever upon it and when the air valve is open, no reverse oscillation, i. e., oscillation in a direction opposite to the normal movement for the purpose, can effect the closing of the air valve. Again, only a normal oscillation of the shoe 18 can affect the valve and then only after the valve has been opened by the action of the releasing plunger and before it is again closed by the spring that is mounted on the air valve stem 27.

When an engine is running backwardly and pulling a train in the direction of traffic, protection is secured by placing the

train carried fixtures on both the right and left ends of the buffer beam, as will be clear to those skilled in the art, and in view of the fact that such duplication is a mere 5 mechanical expedient, illustration thereof is thought to be unnecessary.

In this specification and in the following 10 claims, the word "train" is to be considered in its broadest aspect as meaning any vehicle running on the right of way, and I do not wish to be understood, as limiting, by the use of that term, the use of my invention on a train composed of an engine and cars.

From the foregoing description, taken in 15 connection with the accompanying drawings, it is believed that the complete construction, operation and advantages of my invention will be readily understood by those skilled in the art to which it appertains.

What I claim is:

1. In a device of the class described, a train carried apparatus including an air valve, means holding said valve closed, a 25 device for engaging said holding means to move it to the valve releasing position, said device including a reciprocating plunger, mechanically actuated means for resetting said holding means to thereby reclose said 30 valve, said mechanically actuated means including an oscillatable shaft normally disconnected from said resetting means whereby said shaft may be oscillated without affecting said holding means when said 35 holding means is in its normal position, means for operatively connecting said oscillatable shaft with said resetting means when said holding means has been moved to the valve releasing position, and independent track projections for engaging said 40 plunger and for operating said oscillatable shaft.

2. In an apparatus of the class described, a support, an air operated valve connectible 45 to the train pipe of an air brake system, means for holding said valve closed to maintain the train pipe air pressure under normal conditions, plunger operated means for releasing said holding means to permit said 50 valve to open, a resetting device including an oscillatable shaft and coöperative connections between said oscillatable shaft and said valve holding means for restoring said valve holding means to its normal position, 55 and separate track apparatus for operating respectively said plunger operated releasing means and said oscillatable shaft.

3. In an apparatus of the class described, a support, an air operated valve connectible 60 to the train pipe of an air brake system, means for holding said valve closed to maintain the train pipe air pressure under normal conditions, plunger operated means for releasing said holding means to permit said 65 valve to open, a resetting device including

an oscillatable shaft and coöperative connections between said oscillatable shaft and said valve holding means for restoring said valve holding means to its normal position, separate track apparatus for operating respectively said plunger operated releasing means and said oscillatable shaft, said releasing means being inoperative when the train is moved in a direction opposite to the normal line of travel. 70

4. In an apparatus of the class described, a support, an air operated valve connectible to the train pipe of an air brake system, means for holding said valve closed to maintain the train pipe air pressure under normal conditions, plunger operated means for releasing said holding means to permit said valve to open, a resetting device including an oscillatable shaft and coöperative connections between said oscillatable shaft and said valve holding means for restoring said valve holding means to its normal position, separate track apparatus for operating respectively said plunger operated releasing means and said oscillatable shaft, 75 and a manually operated device coöperatively connected with said holding means for resetting the same. 80

5. In an apparatus of the class described, a support, an air operated valve connectible to the train pipe of an air brake system, means for holding said valve closed to maintain the train pipe air pressure under normal conditions, plunger operated means for releasing said holding means to permit said valve to open, a resetting device including an oscillatable shaft and coöperative connections between said oscillatable shaft and said valve holding means for restoring said valve holding means to its normal position, separate track apparatus for operating respectively said plunger operated releasing means and said oscillatable shaft, 90 and a manually operated device coöperatively connected with said holding means for resetting the same. 95

6. In an apparatus of the class described, a support, an air operated valve connectible to the train pipe of an air brake system, means for holding said valve closed to maintain the train pipe air pressure under normal conditions, plunger operated means for releasing said holding means to permit said valve to open, a resetting device including an oscillatable shaft and coöperative connections between said oscillatable shaft and said valve holding means for restoring said valve holding means to its normal position, 100 separate track apparatus for operating respectively said plunger operated releasing means and said oscillatable shaft, and a manually operated device coöperatively connected with said holding means for resetting the same. 105

6. In an apparatus of the class described, a support, an air operated valve connectible to the train pipe of an air brake system, means for holding said valve closed to maintain the train pipe air pressure under normal conditions, plunger operated means for releasing said holding means to permit said valve to open, a resetting device including an oscillatable shaft and coöperative connections between said oscillatable shaft and said valve holding means for restoring said valve holding means to its normal position, 110 separate track apparatus for operating respectively said plunger operated releasing means and said oscillatable shaft, and a manually operated device coöperatively connected with said holding means for resetting the same. 115

7. In an apparatus of the class described, a support, an air operated valve connectible to the train pipe of an air brake system, means for holding said valve closed to maintain the train pipe air pressure under normal conditions, plunger operated means for releasing said holding means to permit said valve to open, a resetting device including an oscillatable shaft and coöperative connections between said oscillatable shaft and said valve holding means for restoring said valve holding means to its normal position, 120 separate track apparatus for operating respectively said plunger operated releasing means and said oscillatable shaft and a speed controlled manually operable resetting device coöperatively connected with 125

130

said holding means in virtue of which said holding means may be restored to its normal position when the "speed" is below a predetermined degree.

5. In an apparatus of the class described, a support, an air operated valve connectible to the train pipe of an air brake system, means for holding said valve closed to maintain the train pipe air pressure under normal conditions, plunger operated means for releasing said holding means to permit said valve to open; a resetting device including an oscillatable shaft and coöperative connections between said oscillatable shaft and 10 said valve holding means for restoring said valve holding means to its normal position, separate track apparatus for operating respectively said plunger operated releasing means and said oscillatable shaft, said releasing means being inoperative when the train is moved in a direction opposite to the normal line of travel, and a speed controlled manually operatable resetting device co-operatively connected with said holding means in virtue of which said holding means may be restored to its normal position when the "speed" is below a predetermined degree.

8. In a system of the class described, an apparatus which includes a support, an air valve connectible to the train pipe of an air brake system and mounted on said support, a main shaft, a holding cam on said shaft for holding said valve closed, a releasing plunger for engaging said holding cam to release the same and permit said valve to open, a track ramp for operating said plunger, a resetting lever on said shaft, an oscillatable shaft, a cam on said oscillatable shaft 35 for engaging said resetting lever when said holding means has been released, and means for oscillating said shaft to effect said resetting.

9. In a system of the class described, a train apparatus including a support, an air valve mounted in said support and connectible to the train pipe of an air brake system, a main shaft mounted in said support, a valve holding cam on said main shaft 45 for normally holding said valve closed, a plunger carrier held by said support, a releasing plunger mounted in said carrier, said releasing plunger having an air duct, means for effecting communication between said air duct and the train pipe of the air brake system at all times.

10. In a system of the class described, a train apparatus including a support, an air valve mounted in said support and connectible to the train pipe of an air brake system, a main shaft mounted in said support, a valve holding cam on said main shaft 60 for normally holding said valve closed, a plunger carrier, a releasing plunger mount-

ed in said carrier, said releasing plunger having an air duct, means for effecting communication between said air duct and the train pipe of the air brake system at all times, a track ramp for moving said plunger when said support is carried in one direction, and means for holding said plunger carrier to yield when said support is carried in an opposite direction to thereby render said plunger inoperative when engaging said track ramp in "backing."

11. In a system of the class described, train apparatus including a support, an air valve mounted in said support and connectible to the train pipe of an air brake system, a main shaft mounted in said support, a valve holding cam on said main shaft for normally holding said valve closed, a plunger carrier, a releasing plunger mounted in said carrier, said releasing plunger having an air duct, means for effecting communication between said air duct, and the train pipe of the air brake system at all times, a track ramp for moving said plunger when said support is carried in one direction, means for holding said plunger carrier to yield when said support is carried in an opposite direction to thereby render said plunger inoperative when engaging said track ramp in "backing", and means for resetting said holding cam after it has been released.

12. In a system of the class described, train apparatus including a support, an air valve mounted in said support and connectible to the train pipe of an air brake system, a main shaft mounted in said support, a valve holding cam on said main shaft for normally holding said valve closed, a plunger carrier, a releasing plunger mounted in said carrier, said releasing plunger having an air duct, means for effecting communication between said air duct and the train pipe of the air brake system at all times, a track ramp for moving said plunger when said support is carried in one direction, means for holding said plunger carrier to yield when said support is carried in an opposite direction to thereby render said plunger inoperative when engaging said track ramp in "backing", means for resetting said holding cam after it has been released, said last named means including a resetting lever on said main shaft, a balanced oscillatable shaft sustained by said support, and normally disconnected from said resetting lever, a cam on said oscillatable shaft to engage said resetting lever when said holding cam is released.

13. In a system of the class described, train apparatus including a support, an air valve mounted in said support and connectible to the train pipe of an air brake system, a main shaft mounted in said support a valve holding cam on said main shaft

- for normally holding said valve closed, a plunger carrier, a releasing plunger mounted in said carrier, said releasing plunger having an air duct, means for effecting communication between said air duct and the train pipe of the air brake system at all times, a track ramp for moving said plunger when said support is carried in one direction, and means for holding said carrier to yield when said support is moved in an opposite direction to thereby render said plunger inoperative when engaging said track ramp in "backing," means for resetting said holding cam after it has been released, said last named means including a resetting lever on said main shaft, a balanced oscillatable shaft sustained by said support, and normally disconnected from said resetting lever, a cam on said oscillatable shaft to engage said resetting lever when said holding cam is released, a shoe on said oscillatable shaft and a track fixture coöperative with said shoe to oscillate the same and thereby move said resetting cam to effect the resetting operation.
14. In a system of the class described, train apparatus including a support, an air valve mounted in said support and connectible to the train pipe of an air brake system, a main shaft mounted in said support, a valve holding cam on said main shaft for normally holding said valve closed, a plunger carrier, a releasing plunger mounted in said carrier, said releasing plunger having an air duct, means for effecting communication between said air duct and the train pipe of the air brake system at all times, a track ramp for moving said plunger when said support is carried in one direction, and means for holding said plunger carrier to yield when said support is moved in an opposite direction, to thereby render said plunger inoperative when engaging said track ramp in "backing," means for resetting said holding cam after it has been released, said last named means including a resetting lever on said main shaft, a balanced oscillatable shaft sustained by said support and normally disconnected from said resetting lever, a cam on said oscillatable shaft to engage said resetting lever when said holding cam is released, a shoe on said oscillatable shaft and a track fixture coöperative with said shoe to oscillate the same and thereby move said resetting cam to effect the resetting operation, a locking cam on said main shaft, a latch for engaging said locking cam to hold said shaft from accidental turning, and a manually operated restoring device coöperative with the aforesaid parts for effecting the restoration of said holding cam independently of said oscillatable shaft.
15. In a system of the class described, train apparatus including a support, an air valve mounted in said support and connectible to the train pipe of an air brake system, a main shaft mounted in said support, a valve holding cam on said main shaft for normally holding said valve closed, a plunger carrier, a releasing plunger mounted in said carrier, said releasing plunger having an air duct, means for effecting communication between said air duct and the train pipe of the air brake system at all times, a track ramp for moving said plunger when said support is carried in one direction, and means for holding said plunger carrier to yield when moved in an opposite direction to thereby render said plunger inoperative when engaging said track ramp in "backing," means for resetting said holding cam after it has been released, said last named means including a resetting lever on said main shaft, a balanced oscillatable shaft sustained by said support and normally disconnected from said resetting lever, a cam on said oscillatable shaft to engage said resetting lever when said holding cam is released, a locking cam on said main shaft, a latch for engaging said locking cam to hold said shaft from accidental turning, and a manually operated restoring device coöperative with the aforesaid parts for effecting the restoration of said holding cam independently of said oscillatable shaft.
16. In a system of the class described, train apparatus including a support, an air valve mounted in said support and connectible to the train pipe of an air brake system, a main shaft mounted in said support, a valve holding cam on said main shaft for normally holding said valve closed, a plunger carrier, a releasing plunger mounted in said carrier, said releasing plunger having an air duct, means for effecting communication between said air duct and the train pipe of the air brake system at all times, a track ramp for moving said plunger when said support is carried in one direction, and means for holding said plunger to yield when moved in an opposite direction to thereby render said plunger inoperative when engaging said track ramp in "backing," means for resetting said holding cam after it has been released, said last named means including a resetting lever on said main shaft, a balanced oscillatable shaft sustained by said support, and normally disconnected from said resetting lever, a cam on said oscillatable shaft to engage said resetting lever when said holding cam is released, a locking cam on said main shaft, a latch for engaging said locking cam to hold said shaft from accidental turning, and a manually operated restoring device coöperative with the aforesaid parts for effecting the restoration of said holding cam independently of said oscillatable shaft.

- dependently of said oscillatable shaft, and a speed governed latch for said last named restoring device to hold the same inoperative above predetermined speeds.
17. In a system of the class described, train apparatus including a support, an air valve mounted in said support and connectible to the train pipe of an air brake system, a main shaft mounted in said support, a valve holding cam on said main shaft for normally holding said valve closed, a plunger carrier, a releasing plunger mounted in said carrier, said releasing plunger having an air duct, means for effecting communication between said air duct and the train pipe of the air brake system at all times, a track ramp for moving said plunger when said support is carried in one direction, and means for holding said plunger carrier to yield when moved in the opposite direction to thereby render said plunger inoperative when engaging said track ramp in "backing," means for resetting said holding cam after it has been released, said last named means including a resetting lever on said main shaft, a balanced oscillatable shaft sustained by said support, and normally disconnected from said resetting lever, a cam on said oscillatable shaft to engage said resetting lever when said holding cam is released, a shoe on said oscillatable shaft and a track fixture co-operative with said shoe to oscillate the same and thereby move said resetting cam to effect the resetting operation, a locking cam on said main shaft, a latch for engaging said locking cam to hold said shaft from accidental turning, a manually operated restoring device co-operative with the aforesaid parts for effecting the restoration of said holding cam independently of said oscillatable shaft, and a speed governed latch for said last named restoring device to hold the same inoperative above predetermined speeds.
18. In a system of the class described, an apparatus including an air valve, means including a shaft and an arm to engage the valve stem for holding said valve closed, a device including a reciprocable member to push said arm out of the valve stem engaging position for releasing said holding means to permit said valve to open, mechanical means including a second shaft normally disconnected from said first shaft and a mechanical connecting means for operatively connecting said shafts together after said valve has been released for resetting said holding means and thereby reclosing said valve, means for holding said holding means from accidental misplacement, and track obstructions for first actuating said releasing means and then actuating said resetting means.
19. In an apparatus of the class described, a support, an air operated valve connectible to the train pipe of an air brake system, means for holding said valve closed to maintain the train pipe air pressure under normal conditions, plunger operated means for releasing said holding means to permit said valve to open, a resetting device including an oscillatable shaft and co-operative connections between said oscillatable shaft and said valve holding means for restoring said valve holding means to its normal position, and means for holding said holding means from accidental displacement.
20. In a system of the class described, a train carried apparatus which includes a support, an air valve connectible to the train pipe of an air brake system and mounted on said support, a main shaft, a holding cam on said shaft for holding said valve closed, and means for holding said holding means from accidental displacement, a releasing plunger for engaging said holding cam to release the same and permit said valve to open, a track ramp for operating said plunger, a resetting lever on said shaft, an oscillatable shaft, a cam on said oscillatable shaft for engaging said resetting lever when said holding means has been released, and means for oscillating said shaft to effect said resetting.
21. In a system of the class described, a train carried apparatus including a support, an air valve mounted in said support and connectible to the air pipe of an air brake system, a valve holding member mounted in said support, a plunger carrier pivoted in said support to swing in one direction only, a plunger operating in said carrier to engage and release said holding member when said plunger is elevated and when said carrier is in one position, thereby permitting operation of said valve substantially as shown and described.
22. In a system of the class described, a train carried apparatus including a support, an air valve mounted in said support and connectible to the train pipe of an air brake system, a valve holding member mounted in said support, a plunger carrier pivoted in said support to swing in one direction only, a plunger operating in said carrier to engage and release said holding member when said plunger is elevated and when said carrier is in one position, thereby permitting operation of said valve, and a resetting shaft, co-operative connections between said resetting shaft and said holding member to reset the same after said plunger releases said holding member, and means for operating said resetting shaft to cause it to perform its functions.
23. In a system of the class described, a train carried apparatus including a support, an air valve mounted in said support,

- and connectible to the air pipe of an air brake system, a valve holding member mounted in said support, a plunger carrier pivoted in said support to swing in one direction only, a plunger operating in said carrier to engage and release said holding member when said plunger is elevated and when said carrier is in one position, thereby permitting operation of said valve, a track ramp for elevating said plunger when the said apparatus is moving in the direction of travel and to swing said carrier on its pivot when the apparatus is moving in the opposite direction.
24. In a system of the class described, a train carried apparatus including a support, an air valve mounted in said support and connectible to the air pipe of an air brake system, a valve holding member mounted in said support, a plunger carrier pivoted in said support to swing in one direction only, a plunger operating in said carrier to engage and release said holding member when said plunger is elevated and when said carrier is in one position, thereby permitting operation of said valve, a track ramp for elevating said plunger when the said apparatus is moving in the direction of travel and to swing said carrier on its pivot when the apparatus is moving in the opposite direction, and a resetting shaft co-operatively connected with said holding member to reset the same after said plunger has released said holding member, and means for operating said resetting shaft to cause it to perform its functions.
25. In a system of the class described, a train apparatus including a support, an air valve mounted in said support and connectible to the train pipe of an air brake system, a main shaft mounted in said support, a valve holding cam on said main shaft for normally holding said valve closed, a plunger carrier held by said support, a releasing plunger mounted in said carrier, said releasing plunger having an air duct, means for effecting communication between said air duct and the train pipe of the air brake system at all times, and other means for holding said holding cam from accidental displacement.
26. In a system of the class described, a train carried apparatus comprising a support, an air valve mounted in said support and connectible with the train pipe of an air brake system, a holding cam pivoted in said support for co-operating with said valve to hold the same normally closed, a plunger carrier pivoted in said support, a plunger mounted in said plunger carrier to co-operate with said holding cam to effect the release of said cam when said plunger is elevated, means continuously tending to depress said plunger, said plunger having an air duct and connections between said air duct and the train pipe of the air brake system.
27. In a system of the class described, a train carried apparatus comprising a support, an air valve mounted in said support and connectible with the train pipe of an air brake system, a holding cam pivoted in said support for co-operating with said valve to hold the same normally closed, a plunger mounted in said plunger carrier to co-operate with said holding cam to effect the release of said cam when said plunger is elevated, means continuously tending to depress said plunger, means limiting the swinging movement of said plunger carrier in one direction only, a resetting lever co-operatively connected with said holding cam to move with it, a balanced shaft, a member on said balanced shaft to engage said resetting lever when said resetting lever is out of its normal position to reset the parts.
28. In a system of the class described, a train carried apparatus comprising a support, an air valve mounted in said support and connectible with the train pipe of an air brake system, a holding cam pivoted in said support for co-operating with said valve to hold the same normally closed, a plunger mounted in said plunger carrier to co-operate with said holding cam to effect the release of said cam when said plunger is elevated, means continuously tending to depress said plunger, means limiting the swinging movement of said plunger carrier in one direction only, a resetting lever co-operatively connected with said holding cam to move with it, a balanced shaft, a member on said balanced shaft to engage said resetting lever when said resetting lever is out of its normal position to reset the parts, and a manually operatable speed controlled resetting device operative below a predetermined speed and co-operatively connected with said holding cam for resetting the same.
29. In a system of the class described, a train carried apparatus comprising a support, an air valve mounted in said support and connectible with the train pipe of an air brake system, a holding cam pivoted in said support for co-operating with said valve to hold the same normally closed, a plunger carrier pivoted in said support, a plunger mounted in said plunger carrier to co-operate with said holding cam to effect the release of said cam when said plunger is elevated, means continuously tending to depress said plunger, means limiting the swinging movement of said plunger carrier in one direction only, a resetting lever co-operatively connected with said holding cam

to move with it, a balanced shaft, a member on said balanced shaft to engage said resetting lever when said resetting lever is out of its normal position to reset the parts, a
5 manually operable speed controlled resetting device operative below a predetermined speed and coöperatively connected

with said holding cam for resetting the same, and means preventing the accidental displacement of said holding cam.
